(57) **CLAIM**

The ornamental design for an add-on module for an access reader, as shown and described.

DESCRIPTION

FIG. 1 is a front isometric view of an add-on module for an access reader, showing my new design;

FIG. 2 is a rear isometric view of the module of FIG. 1;

FIG. 3 is a front view of the module of FIG. 1;

FIG. 4 is a rear view of the module of FIG. 1;

FIG. 5 is a left side view of the module of FIG. 1;

FIG. 6 is a right side view of the module of FIG. 1;

FIG. 7 is a top view of the module of FIG. 1;

FIG. 8 is a bottom view of the module of FIG. 1;

FIG. 9 is a front isometric view of the module of FIG. 1 coupled with an access reader;

FIG. 10 is a rear isometric view of the module and access reader of FIG. 9;

FIG. 11 is a front view of the module and access reader of FIG. 9;

FIG. 12 is a rear view of the module and access reader of FIG. 9;

FIG. 13 is a left side view of the module and access reader of FIG. 9;

FIG. 14 is a right side view of the module and access reader of FIG. 9;

FIG. 15 is a top view of the module and access reader of FIG. 9; and,

FIG. 16 is a bottom view of the module and access reader of FIG. 9.

The broken lines of FIGS. 2, 4, 8, and 9-16 are provided for purposes of illustration and form no part of the claimed design of the present application. However, the broken lines are intended to provide explicit disclosure as to presently unclaimed portions of the design, and Applicants reserve the right to pursue and claim such other presently unclaimed portions, alone or in combination with the presently claimed portions, in one or more continuation applications. Applicants further explicitly reserve the right to pursue and claim, in one or more continuation applications, a subset of the presently claimed design or a different subset of the presently claimed and presently unclaimed portions illustrated in the figures.

1 Claim, 12 Drawing Sheets
